UNITED STATES PATENT OFFICE.

JAMES WILLIAM MORRISON AND THOMAS WILLIAM HOLT, OF STALEYBRIDGE,
ENGLAND.

DOUBLING, TWISTING, AND WINDING AND SUCH LIKE MACHINE.

Application filed August 10, 1921. Serial No. 491,068.

To all whom it may concern:

Be it known that we, JAMES WILLIAM MORRISON and THOMAS WILLIAM HOLT, subjects of the King of Great Britain and Ireland, residing, respectively, at 66 Astley Street, Staleybridge, in the county of Chester, England, and 32 Mottram Road, Staleybridge, aforesaid, have invented new and useful Improvements in or Connected With 10 Doubling, Twisting, and Winding and Such like Machines, of which the following is a specification.

This invention relates to doubling, twisting, and winding and such like machines, 15 as for example doubling frames of the kind in which a package carrier is supported on a spindle run at a high speed and in which the yarn is traversed in front of a revolving friction drum and laid upon a paper tube 20 or other support to produce a cheese or bobbin, the tube being held against the friction drum by the action of a weighting device which maintains the friction as the cheese is built-up.

25 The object of our invention is to produce a very solid, well-wound and perfectly symmetrical cheese or the like.

When smooth paper tubes are used, the friction during the early stages of winding-on is frequently not adequate although the 30 weighting motion may be quite adequate during the later stages of winding-on. With an inadequate weight in the early stages, due to lack of proper friction, the layers 35 nearest to the tube may be softly wound producing as it were a soft or spongy base or centre to the cheese which soft or spongy base or centre may also cause the twist to vary at different portions of the cheese. When later, 40 as the cheese is gradually built-up and the effect of the loading is adequate, the shape of the cheese is even thereafter adversely affected by the soft base or centre.

A solution, which suggests itself would be 45 to use a heavier weight on the weighting motion, but in effect this is not a solution, because (apart from difficulties in accommodating a large weight) as the cheese grows, additional weight is a distinct draw-back because the friction as the cheese grows becomes so great as to effect the winding at such a degree of pressure and under such tension that the ends tend to bulge out, thus 50 destroying the symmetry of the cheese.

55 According to our invention we employ two

weighting motions, a main weighting motion, and, an auxiliary or secondary weighting motion which acts upon the main weighting motion or otherwise upon the tube carrier for the end in view, such auxiliary or secondary weighting motion being of such a construction that during the early stages of the winding-on it exercises its maximum effect, the weighting effect automatically diminishing as the cheese reaches a larger diameter. We can also so construct such auxiliary or secondary weighting motion that its effect may become nil when a certain diameter is reached.

The simplest solution is to use a weighted lever device so fulcrumed and so acted upon by the main weighting motion that initially such weighted lever exercises its maximum effect, but, as winding-on proceeds, such auxiliary weighted lever is so influenced as to gradually take the weight out of action.

We do not restrict ourselves as to construction so long as this principle of increase of load initially is utilized with a gradual diminution of said auxiliary load.

The attached drawings illustrate means for carrying out our object according to the system above indicated, and in the said drawings:—

Fig. 1 is a diagram of a type of doubling frame employing a movable weighting motion in connection with each friction drum and shows a simple type of auxiliary or secondary weighting motion in conjunction therewith, the frame being double sided, the mechanism on the right not being fully shown as same is a mere duplication.

Fig. 2 shows separately a broken side elevation of a weighting motion with the auxiliary or secondary weighting motion combined therewith.

Fig. 3 is a back view of the arm seen in Fig. 2.

Fig. 4 shows a plan view of the slidable bar, etc.

Fig. 5 is a detail plan.

Fig. 6 is also a detail plan of the upper part of the weighting frame and should be examined with Fig. 2.

The drawings show our invention in connection with a swing frame type of loading mechanism, each set of which comprises a slidable bar 1 which passes over a bowl 2, through a bracket 3 bolted to the rail 4.

This slideable bar is loaded by a load lever 5, fulcrumed at 6, said load lever having an adjustable stud 7 which bears on the slideable bar 1 and loads the same.

5 The slideable bar 1 is shown bifurcated at its inner extremity (see Fig. 4) thus producing shoulders 1^x and a fork which is bored for the pivotal stud of an arm 8 attached to the frame 9, which carries the 10 spindle or support for the paper tube or the like upon which the yarn is wound. As is shown, the frame 9 has open slots or bearings 10 which engage the shaft 11 thus producing a bearing for the frame 9 allowing 15 said frame to move angularly.

The bottom of each slideable bar 1 has a lug 12 for a purpose to be described.

Supported by the spring-pieces 13 or frame-work of the machine, are small brackets 14 which have gaps for small diameter shafts 15, said shafts being fixed by pinching studs or otherwise.

On each shaft, and with respect to each weighting head or frame 9, we mount a 25 shaped lever 16, the lever having an open slot 17 to fit on the shaft 15. The forward part of the lever 16 is bifurcated at 18 or shaped like a fork to allow the slideable bar 1 to work therethrough whilst the rear part 30 of the lever is a shaped weight 16^x. In lieu of this the auxiliary loading device may consist of a shaped casting having a rearwardly projecting shank on which an adjustable weight is carried.

35 When winding commences on the tube or the like supported by the frame 9, the fork or arms 18 of the auxiliary or secondary loading lever 16 project upwards and bear against the shoulders 1^x of the fork on the slideable bar 1 and the weight itself is substantially horizontal. This means a maximum loading, because the weight 16^x is added to the weight of the swing loading frame 9, etc. As the winding-on proceeds, and the cheese is built-up, the slideable bar 1 moves forward, and, acting on the fork or arms 18 of the auxiliary lever 16, turns same down through an arc and raises the weight itself through an arc, thus turning such weight sooner or later into a vertical position or one approximating thereto, at which stage, the auxiliary or secondary loading device ceases to exercise any material weighting effect. The lug 12 on the slideable bar 1 by engaging the fork 18 always maintains the auxiliary loading device 16 in a true position permitting instant re-setting by pushing-in of the slideable bar 1, or, as is more convenient, by the operator elevating 50 the loading lever 5 when after doffing the weight of the frame 9 and its parts cause instant re-setting.

Our auxiliary or secondary loading device may be otherwise connected up to the 60 loading swing frame.

Although we have referred to the winding of cheeses such reference is only by way of example.

The arm 8 has a prepared face 8^x and is connected to a prepared face 9^x on the frame 9 by a stud passing through a slot 19 in the arm 8. This permits the frame 9 to assume a position not parallel with the friction drum *d* allowing of conical bobbins being supported on the spindle in the frame 9, it being clear that by a variation in the setting of the studs 20, 20 to cause one to bear on the shaft 11 the frame 9 can be inclined or thrown out of the horizontal.

We declare that what we claim is:

1. In yarn doubling, twisting and winding machines a friction drum, bearings therefor, a primary weighting frame having means for supporting a package consisting of a frame, a fulcrum for said frame, a slideable member attached to said frame, a fulcrumed weighting device acting upon said slideable member, and automatically operative loading means combined with said slideable member for varying the constraining effect of said automatically operative loading means during the building up of a cheese or the like.

2. In yarn doubling, twisting and winding machines, a friction device, bearings therefor, a primary weighting frame adapted to receive and permit rotation of a package carrier and to yieldingly constrain said package carrier with respect to the friction device, a fulcrum for the frame, a jointed sliding element displaced as building-up takes place and an auxiliary weighting and automatically operative means which exerts a diminishing loading effect on the frame structure, the jointed sliding element acting 105 upon the auxiliary weighting means.

3. In yarn doubling, twisting and winding machines, the combination of a friction drum, primary weighting means adapted to receive a spindle or support for a package carrier and to press same towards the friction drum, a fulcrum for the weighting means, a slideable element jointed to the weighting means, a pivoted load acting on the slideable element, supplementary weighting means acting on the primary weighting means, said supplementary weighting means being operated by provided parts for automatically rendering their action ineffective as building-up of the cheese or the like takes place.

4. In yarn doubling, twisting and winding machines, the combination of a friction drum, supports therefor, a primary weighted swing frame, means for supporting a spindle for the package carrier in the frame, a fulcrum for the frame, connections from the structure including a slideable element, a fulcrumed weight acting on the slideable element, an auxiliary weighting member mov-

able upon a fulcrum and co-operating with the primary weighting frame, said auxiliary weighting member being automatically operative to diminish the weighting effect of the auxiliary member and to move same into approximately an inoperative portion as set forth.

5. In a yarn doubling, twisting and winding machine the combination of a friction surface, bearings therefor, means in the form of a primary weighting frame to receive a spindle or support for a package carrier, said frame pressing the spindle to said friction surface, an extension from the

frame, a slideable element jointed to said extension, a weight device acting on the slideable element, the whole constituting a primary weighting motion, and an auxiliary weighting motion working upon a fulcrum and adapted to initially load the primary weighting motion, said auxiliary weighting motion having a diminishing effect on the primary weighting motion as set forth. 15
20

In testimony whereof we have signed our names to this specification.

JAMES WILLIAM MORRISON.

THOMAS WILLIAM HOLT.
